UNITED STATES PATENT OFFICE.

LOUIS VASTANO, OF EAST PROVIDENCE, RHODE ISLAND.

DESIGN FOR A SCAPULAR FINGER RING.

Application filed August 30, 1926. Serial No. 18,904. Term of patent 14 years.

To all whom it may concern:

Be it known that I, LOUIS VASTANO, a citizen of the United States, residing at East Providence, in the county of Providence and State of Rhode Island, have invented a new, original, and ornamental Design for a Scapular Finger Ring, of which the following is a specification, reference being had to the accompanying drawing, forming a part thereof.

Figure 1 is a top plan view of a scapular finger ring showing my design.

Figure 2 is an elevation of one side of the ring.

Figure 3 is an elevation of the other side of the ring, and

Figure 4 a diametrical section of the same.

I claim:

The ornamental design for a scapular finger ring, as shown.

LOUIS VASTANO.
